UNITED STATES PATENT OFFICE.

SYLVANUS C. EVANS, OF PROVIDENCE, RHODE ISLAND.

DOOR GUIDE.

Application filed February 11, 1922. Serial No. 535,889.

This invention relates to a guiding device for correcting the elevation of the free edge of a door upon being swung to closed position so as to cause the latch and the bolt of the door to accurately enter their corresponding sockets in the jamb portion of the door-frame formed to receive them, and the object of this invention is to provide a grooved member adapted to set into the jamb portion of the door-frame and a co-operating guiding member extending from the edge of the door and adapted to enter said grooved member to lift the edge of a door that has sagged so that the bolt and latch members will operate properly when the door is closed.

With these and other objects in view, the invention consists of certain novel features of construction, as will be more fully described, and particularly pointed out in the appended claim.

In the accompanying drawings:

Figure 1 is a perspective view illustrating the socket member as inserted into the jamb portion of a door-frame and the tongue member as secured to the edge of the door and in position to engage the grooved member when the door is swung closed.

Figure 2 is a perspective view of the grooved plate removed from the door-jamb.

Figure 3 is a face view of the tongue member mounted on its plate removed from the door.

Figure 4 is a view illustrating the tongue member as just about to enter the grooved member so as to lift the edge of the door into position upon being moved to closed position.

Figure 5 is a sectional view illustrating the tongue member as engaging the grooved member for the purpose of correcting the elevation of the free edge of the door.

It is found in practice particularly with heavy swinging doors, that the free edge of the door almost always sags to some extent causing the bolt and latch members of the door to move out of registering position with the sockets in the corresponding socket plate in the jamb of the door-frame so that the latch will not catch and the bolt will not enter properly, and the following is a detailed description of one means by which this defect may be remedied:—

With reference to the drawings, 10 designates the grooved-plate guiding-member which comprises essentially a pair of parallel, spaced-apart guide-bars 11 connected by

a cross-bar 12 which is set inwardly beyond the plane of the outer surface of the guide bars 11 forming a groove between them for the reception of the guide tongue, presently described.

This grooved plate is adapted to set into the jamb portion 13 of the door-frame flush with the face of the jamb and be secured therein by screws 14 and these guide bars 11 of this plate are preferably of sufficient length to extend outwardly beyond the entering edge of the door jamb to serve as a guide for the edge of the door to engage and force back a sagging door into alignment with the jamb as it is moved to closed position.

The adjacent edges at the outer ends of these bars are preferably rounded off as at 15 or formed slightly tapering so as to provide an enlarged mouth portion to facilitate the entrance of the guide tongue as the door swings to closed position.

The guide tongue member 16 comprises essentially a plate 17 on the outer face of which is mounted an elongated bar or tongue 18, the length of this plate being preferably about the width of the door and is adapted to set into the outer face of its swinging edge practically flush therewith leaving the tongue portion 18 extending beyond the plane of this outer edge and this plate may be secured to the door by means of screws 19, or otherwise, the tongue being disposed transversely of the edge of the door.

The entering end 20 of this tongue is preferably rounded off on both its upper and lower edges so as to facilitate its entering the space between the guide bars 11 in the groove plate.

As the door is swung inwardly to closed position the tapering end of this tongue usually engages the lower edge of the guide bars 10 and so serves to lift the free edge of a sagging door and bring its bolt 21 and latch 22 into correct alignment with the bolt-receiving socket 23 and the latch-receiving socket 24 both in the jamb portion of the door-frame whereby both the bolt and the latch will properly enter their respective sockets which is not the case with the ordinary door not equipped with my improved device, when it sags.

My improved door-guide is very simple and practical in construction and effective in its operation and when applied to a door it accurately corrects the vertical alinement of

the same although it may have sagged to considerable extent out of its proper operating position.

The foregoing description is directed 5 solely towards the construction illustrated, but I desire it to be understood that I reserve the privilege of resorting to all the mechanical changes to which the device is susceptible, the invention being defined and 10 limited only by the terms of the appended claim.

I claim:

A door guide comprising a grooved plate set into the jamb portion of a door-frame, 15 the lower edge of said groove being hard

and set in a horizontal plane and having a portion extending beyond the edge of the jamb said extending portion having a downwardly curved tongue-receiving edge, and a cooperating guide tongue member fixed 20 transversely to the edge of the door and having a hard horizontally disposed lower engaging edge and a tapered end adapted to enter the groove in said jamb plate as the door closes to guide the edge of the door accurately to its correct elevation to cause the latch and lock-bolt to register with their receiving openings.

In testimony whereof I affix my signature.

SYLVANUS C. EVANS.
